UNITED STATES PATENT OFFICE.

GEORGE SIMPSON AND JOHNSTON R. GORDON, OF NEW YORK, N. Y.

BILGE-TUNNEL FOR SHIPS.

1,118,956.

Specification of Letters Patent. Patented Dec. 1, 1914.

Application filed October 11, 1913. Serial No. 734,558.

To all whom it may concern:

Be it known that we, GEORGE SIMPSON and JOHNSTON R. GORDON, citizens of the United States, residing at New York city, 5 in the county of New York and State of New York, have invented certain new and useful Improvements in Bilge-Tunnels for Ships, of which the following is a specification.

10 This invention relates to improvements in the arrangement and construction of ships' shaft tunnels, and has for its object to lighten construction and to eliminate the obstruction to stowage in the holds of vessels caused by shaft tunnels when arranged and built in the usual way.

It is well known that vessels propelled by screws have a shaft tunnel or tunnels built through the center of the cargo holds 20 through which the shafting transmits the power from the prime mover to the propeller, and that these tunnels encroach upon, and deduct considerably from the hold capacity, as well as obstructing and breaking up the stowage of cargoes and interfering 25 in the case of bulk cargoes such as coal, sulfur and ores, with the grab buckets used in discharging these cargoes. In some cases, the broken stowage thus caused is so considerable, that owners and shipbuilders have resorted to the expedient of fitting a watertight platform, or deck, to inclose the shafts in a separate hold with its attendant loss 30 in cargo capacity. These tunnels, and this alternative of fitting a watertight platform or deck, result in the addition of much material to the vessel's structure, and, in order 35 therefore to lighten the construction and to remove the objectionable features of 40 broken stowage, and also the obstruction caused by the tunnels to the use of the grab or other cargo discharging implements, we have discovered that with certain types of 45 prime movers it is possible to arrange and construct what we term "bilge tunnels"

around a space inclosed by the interior bilge of the vessel as shown by the accompanying drawings, and substantially in the manner hereinafter described.

In the annexed drawings in which similar 50 numerals refer to like parts in all the figures:—Figure 1 is a longitudinal section of a vessel. Fig. 2 is a hold plan of the same vessel. Fig. 3 shows a transverse section through the hold of this vessel. Figs. 4 and 55 show alternative forms of bilge tunnels.

1 indicates the watertight spaces inclosed to form the bilge tunnels through which the propeller shafting, 2 is carried. The inner or hold walls 3 of these tunnels are formed 60 by steel plating and supported and connected to the tunnel frame 4, which are preferably inside the bilge space as shown in Figs. 3, 4 and 5. These hold walls 3, 65 may be constructed as shown in Fig. 3, with a horizontal top and a vertical side or they may both be sloped as shown by Fig. 4, or the top sloped and the side vertical or by other variation in their geometrical form.

In Figs. 1 and 2 the machinery compartment is indicated by 5 and the prime movers or propelling engines installed in the wings thereof by 6. The stern tubes are shown in both figures by the numeral 7 and the hold of the vessel by 8. 70 75

Having now particularly described and ascertained the nature of our said invention, and in what manner the same is to be performed, we declare that what we claim is:—

Shaft tunnels constructed in the bilges of 80 vessels and extending from the machinery compartment to the stern tubes, substantially as described.

In testimony whereof we affix our signatures in presence of two witnesses.

GEORGE SIMPSON.

JOHNSTON R. GORDON.

Witnesses:

ARTHUR R. FALLON,

ARCHIBALD MCINTOCK.
